UNITED STATES PATENT OFFICE.

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL.

Specification forming part of Design No. 6,388, dated February 11, 1873.

To all whom it may concern:

Be it known that I, FREDERICK WINK, of city and county of Philadelphia, State of Pennsylvania, have invented a Design for a Shawl-Pattern, of which the following is a specification:

The main features of my design, which is fully illustrated in the accompanying drawing, are the alternate wide and narrow stripes A and B, each composed of a series of minor parallel stripes of different widths and shades or colors, and some of the said minor stripes in the main stripe A being blended or shaded gradually into each other, as shown. The central ribs a and a' of the two main stripes are

precisely alike, and are elaborately ornamented, the character of the ornamentation being so clearly illustrated in the drawing as to render description unnecessary.

Irrespective of the colors employed, I claim—

1. The design for the minor stripes a a' , as shown.

2. The design for the whole pattern, as shown.

In testimony whereof I have signed my name to this specification in the presence of two subscribing witnesses.

FRED. WINK.
